UNITED STATES PATENT OFFICE.

WILLIAM W. WEEKS, OF BROOKLYN, NEW YORK, ASSIGNOR TO ELEVATOR SUPPLIES COMPANY, INC., A CORPORATION OF NEW JERSEY.

ELECTRIC SWITCH.

Application filed May 25, 1923. Serial No. 641,310.

To all whom it may concern:

Be it known that I, WILLIAM WALLACE WEEKS, a citizen of the United States, residing at 366 4th St., Brooklyn, New York, have invented a certain new and useful Improvement in Electric Switches, of which the following is a clear, full, and exact description.

This invention relates to an electric switch, and more particularly to an improved switch for opening and closing the controller circuit of an elevator with the opening and closing of the elevator door.

In the operation of elevators, it is essential that a switch be employed for breaking the electrical operating circuit when the elevator door is open, so as to render it impossible to start the elevator, by accident or otherwise, while the elevator door is open.

Various forms of switches have been employed for this purpose, but the switches heretofore used have been unsatisfactory for the reason that with continual use the switches become worn and produce bad contacts resulting in sparking. Such sparking, or arcing across the points of contact, frequently burns off the points of contact on the contacting members so that rapid deterioration of the switch takes place and a very poor and inefficient operation of the elevator results.

It is the primary object of the present invention to provide an improved switch in which the objectionable features above noted are overcome.

A second object of the invention is to provide a switch of a form in which wear will be diminished so as to attain a considerably longer life of the switch.

Another object of the invention is to provide means whereby the switch when operated shall maintain substantially perfect contact while current is passing through the switch, and which shall maintain substantially perfect insulation when the electrical circuit is broken.

Another object of the invention is to provide a switch particularly adapted for elevator operation in which the circuit breaking means operates substantially instantaneously to force the contacting or conducting means apart instead of rolling away from the points of contact as in the form of switch generally employed for this purpose.

Another object of the invention is to pro-

vide a switch of a form which, if through accident or intention it is called upon to make and break contact in a circuit, will operate satisfactorily for this purpose and stand such extra duty.

With these and other objects in view, the invention comprises various features hereinafter described and particularly defined in the claims.

The invention may be best understood by describing it in connection with the accompanying drawings, in which—

Fig. 1 is a view in elevation of the switch with the front cover plate removed;

Fig. 2 is a horizontal section of the switch taken on the line 2—2 of Fig. 1; and

Fig. 3 is a horizontal section of the device on the line 3—3 of Fig. 1, showing the switch operating lever attached to the cam pivot.

The preferred form of the invention comprises a casing 10 having a base 12 in which are openings 14 and 16 through which the leads from a circuit are adapted to pass to connect with terminals 18, 20, of the usual form. The terminals 18, 20 are suitably connected by means of conducting wires 22, 24 to conducting bars 26, 28 preferably of brass or copper, which are pivotally supported on pivots 25, 27 within the casing, as shown in Fig. 1 of the drawings. At their points of support, the bars are separated by means of insulating material which extends downwardly therefrom in order to prevent short circuiting across the bars. At their lower ends the bars 26, 28 are extended outwardly and positioned between the lower ends thereof is a cam or movable member 30, having conducting and insulating portions thereon by means of which the circuit through the bars may be made and broken. The conducting portions of the movable member comprise conducting segments 32, 34 which are connected by means of conducting bars 36, 38 so that when the segments are in contact with the bars 26, 28, the circuit will be completed. The conducting segments 32, 34 are preferably substantially circular and are placed in positions diametrically opposite each other in corresponding depressions on the surface of the cam or movable member 30. Adjacent the ends of the segments 32, 34, are insulating portions 40, 42 which are preferably integral with the body of the cam or movable member and which project outwardly forming raised or nosed portions on

diametrically opposite faces of the movable member. The movable member is substantially elliptical in form, the distance between the segments 32, 34 being the minor axis thereof, and the distance between the outer portions of the insulating sections 40, 42 comprising the major axis of the ellipse. Between the end portions of the segments 32, 34 and the insulating sections 40, 42, are air gaps 44, 46, 48 and 50 by means of which increased insulation is attained between the conducting segments and the insulating portions of the movable member. In order to keep the bars 26, 28 continually in contact with the surfaces of the movable member 30, I provide springs 52, 54 which are preferably helical in form and supported by means of lugs 56, 58 attached to the bars 26, 28 respectively. The outer ends of the helical springs are supported upon the surface of insulating members 60, 62 which are shown in cross section in Fig. 2 of the drawings. The movable member 30 is suitably supported upon a bar or pivot 64 to which it is attached by any suitable means, such, for example, as a pin passing through a slot in the movable member and the pivot. The pivot 64 is attached to a lever 66 which is connected to an operating mechanism by which the switch is operated. When the lever is attached to the toggle levers of an elevator door, for example, the switch will be operated with movements of the door. The switch may be so connected as to break the elevator operating circuit when the elevator door is opened a predetermined amount, thus rendering operation of the elevator by means of the control lever impossible while the door is open beyond that predetermined amount. The operation of the switch in connection with the controller circuit of an elevator is as follows:

When the elevator door is opened by means of the toggle levers, a bar connected to the lever 68 moves the lever which in turn rotates the cam or movable member 30 so that the insulating portions 40, 42 thereof come into contact with the bars 26, 28, spreading them outwardly against the yieldable springs 56, 58, causing an interruption of the current passing through the elevator operating circuit. In this position of the movable member 30, the elevator cannot be operated by means of the controller lever in the elevator, and no movement of the elevator is therefore possible until the circuit is again closed by the operation of the movable member. When the door is closed, the various levers are again operated so that the movable member is turned in the position in which the conducting segments 32, 34 are in contact with the bars 26, 28. The circuit through the bars is thus completed, and the elevator may then be operated by means of the controller lever.

By the spreading action of the extended insulating portions of the movable member 30 of the switch, the bars 26, 28 are forced rapidly outwardly against the tension of the springs 56, 58 and as soon as the movable member is turned into position for closing the circuit through the bars, the bars 26, 28 are suddenly and forcibly thrown inwardly against the contacting surfaces by means of the springs, and a substantially perfect contact is therefore made between the surfaces of the segments and the bars. By this means, sparking at the contact surfaces of the switch is prevented, which results in an increased life of the switch.

It is to be understood that the device which has been described is not limited in its application to elevator operating circuits, but may be employed in connection with any other mechanism to which it is adapted. It is also to be understood that various modifications and changes may be made in the device as described without departing from the spirit and scope of the invention.

Having thus described the invention, what is claimed as new is:

1. An electric switch comprising circuit terminals, conducting bars connected to said terminals, a movable member mounted between said conducting bars, means for maintaining said bars in contact with said member, circular conducting arcs mounted on said member whereby said bars remain stationary in position when in contact with said arcs, conducting means in said movable member between said arcs, and non-conducting portions on said movable member extending outwardly thereon whereby when said movable member is operated to attain contact between said non-conducting portions and said bars the latter will be moved outwardly and the circuit through said movable member will be broken.

2. An electrical switch comprising spring-pressed conducting bars, a substantially elliptical movable member pivotally positioned between the bars, said movable member having diametrically opposite conducting members upon the minor axis of the said elliptical member and diametrically opposite insulating portions on the major axis of the said elliptical member, and means for operating the movable member to connect the said conducting members in series with the said conducting bars.

3. An electrical switch comprising a movable member having diametrically opposite conducting portions thereon and diametrically opposite insulating portions thereon, the distance between the insulating portions being greater than that between the conducting portions, conducting bars pivotally placed with respect to the said

- movable member so as to spread with the movements of the said movable member when the insulating portions thereof are in contact with the said bars, and spring means 5 adapted to maintain the said bars into contacting relation with the said movable member.
4. An electrical switch comprising a movable insulating member having diametrically opposite conducting portions thereon in the form substantially of circular segments, the said insulating member having projecting nosed insulating portions between the said segments, conducting bars pivotally placed with respect to the said movable member so as to yield with the movements of the said movable member, and spring means adapted to maintain the said bars in contact with the said movable member.
- 10 5. An electrical switch comprising a movable insulating member having diametrically opposite conducting portions thereon in the form of substantially circular segments, the said insulating member having nosed insulating portions between the said

segments, conducting bars pivoted at one end and extending to contact with opposing sides of the said movable member so as to yield with movements of the said member, the said conducting portions being so placed 30 on the said movable member as to break contact with the said bars substantially simultaneously, and the said nosed portions being so positioned as to cause the said bars to spread rapidly with a speed depending upon the speed of movement of the said movable member and the distance of the nosed portions from the pivoted ends of the said bars.

6. An electric switch comprising a movable member having diametrically opposite 40 conducting surfaces and diametrically opposite insulating surfaces thereon, the distance between the insulating surfaces being greater than that between the conducting surfaces and conducting bars adapted to be 45 held in pressure contact with opposite surfaces of said member.

Signed at New York city, N. Y. this 24th day of May 1923.

WILLIAM W. WEEKS.
